US00D981271S

(12) **United States Design Patent** (10) **Patent No.:** **US D981,271 S**
Crawford et al. (45) **Date of Patent:** **** Mar. 21, 2023**

(54) **BUCKLE**

(71) Applicants: **John Crawford**, Canton, NC (US);
Kyle Chumchal, Fletcher, NC (US);
Anthony Louis Marfione, Mills River,
NC (US)

(72) Inventors: **John Crawford**, Canton, NC (US);
Kyle Chumchal, Fletcher, NC (US);
Anthony Louis Marfione, Mills River,
NC (US)

(73) Assignee: **Microtech Knives, Inc.**, Mills River,
NC (US)

(**) Term: **15 Years**

(21) Appl. No.: **29/780,589**

(22) Filed: **Apr. 26, 2021**

(51) LOC (14) Cl. **02-07**

(52) U.S. Cl.
